UNITED STATES PATENT OFFICE.

JOHN EDMAN, OF MINNEAPOLIS, MINNESOTA, ASSIGNOR OF ONE-HALF
TO ALFRED M. HOVLAND, OF MINNEAPOLIS, MINNESOTA.

GRAIN-DOOR FOR CARS.

No. 856,775.

Specification of Letters Patent.

Patented June 11, 1907.

Application filed January 2, 1907. Serial No. 350,361.

To all whom it may concern:

Be it known that I, JOHN EDMAN, a citizen of the United States, residing at Minneapolis, in the county of Hennepin and State of Minnesota, have invented certain new and useful Improvements in Grain-Doors for Cars; and I do hereby declare the following to be a full, clear, and exact description of the invention, such as will enable others skilled in the art to which it appertains to make and use the same.

My invention has for its object to provide a grain door of improved construction, and to this end it consists of the novel devices and combinations of devices hereinafter described and defined in the claims.

In the accompanying drawings which illustrate the invention, like characters indicate like parts throughout the several views.

Referring to the drawings, Figure 1 is a view in elevation, showing the central portion of the body of a car to which one of my improved grain doors is applied. Fig. 2 is a vertical section taken on the line $x^2 x^2$ of Fig. 1. Fig. 3 is a horizontal section taken on the line $x^3 x^3$ of Fig. 1. Fig. 4 is a horizontal section taken on the line $x^4 x^4$ of Fig. 1, some parts being removed. Fig. 5 is a skeleton view in front elevation, showing the grain door locking plates and actuating mechanism therefor. Fig. 6 is a detail in horizontal section on the line $x^6 x^6$ of Fig. 1. Fig. 7 is a view corresponding to Fig. 6, but illustrating different positions of the parts. Fig. 8 is a view corresponding to Fig. 2, but illustrating a modified construction; and Fig. 9 is a horizontal section taken on the line $x^9 x^9$ of Fig. 8, some parts being broken away.

The numeral 1 indicates the car body having at its sides the usual door openings formed between door posts 2. Rigidly secured to the inner edges of the door posts 2 are stop cleats 3 that extend preferably about half-way up the same. Formed in the door posts 2, outward of the stop cleats 3 and extending from top to bottom thereof, are vertical grooves or seats 4 in which work vertically extended pivoted lock plates 5 having trunnions 6 at their ends, which trunnions 5 are mounted in suitable bearings 7 at the top and bottom of the door frame. Spur pinions 8 are secured to the upper trunnions 6, and these pinions mesh with the outer teeth of

racks 9. The racks 9, at their inner ends, have teeth that mesh with the opposite sides of a spur pinion 10 carried by a short vertical shaft 11 suitably mounted in the top of the door frame, at the center thereof, and provided with an operating lever 12.

The numeral 13 indicates the main section 60 of the grain door, which grain door is of such width that it will swing between the door posts 2, when the lock plates 5 are turned entirely into their seats 4, as shown in Fig. 7. When this grain door is in operative position, 65 it is tightly pressed against the inner stop cleats 3, by the lock plates 5, which lock plates are held in the operative positions shown in Figs. 1, 3, 5 and 6, when the lever 12 and racks 9 are in the position shown in Figs. 4 and 5. By the lock plates 5, the said door 13 may be pressed against the stop cleats 3 under such tension that said door can not be moved vertically. The grain door 13 is provided with a folding supplemental section 75 13^a connected to the upper edge thereof by hinges 14. The hinges 14 have a common coupling bolt in the form of a long rod 15, the ends of which project slightly beyond the ends of the grain door and terminate in eyes 80 16. The eyes 16 work loosely on guide rods 17, the ends of which guide rods are secured to the door posts 2 and to the overlying roof beams 1^a of the car. The said guide rods 17 extend vertically nearly to the tops of the 85 door posts 2, are then curved inward and extended horizontally to or approximately to the center of the car, where, as shown, they are anchored by suitable fastenings 18. The hinge rod 15, it will thus be seen, is free to 90 oscillate with respect to the hinges 14 and with respect to both door sections 13 and 13^a. On the door 13, near the edges thereof, are lugs or projections 13^b that engage with perforations or seats 5^a in the lock plates 5, and thereby positively hold said door against upward movements when said lock plates are 95 pressed against the same.

When the grain door is released by the lock plates 5, the supplemental section 13^a is 100 adapted to be turned inward and downward against the main door 13, and the latter, together with the said folded section 13^a may then be slid upward on the guide rods 17 and secured in the position shown by dotted lines 105 in Fig. 2, the free out-turned edge of the said

section 13 being then supported by a suitable bracket 19 on the side of the car near the top thereof.

When it is desired to completely close the door opening, an additional door section 13^b may be provided. This door section 13^b, like the door sections 13 and 13^a, is adapted to be held against outward movement by the lock plates 5. It is provided with guide lugs or eyes 20 that work slidably upon curved guide rods 21 located above the guide rods 17 and secured to the posts 2 and beams 1^a. The door sections 13^a and 13^b are preferably provided with pivotally and slidably mounted lock bolts 22 that engage with the in-turned clamping plates 5, to secure the said door sections thereto against inward movement.

In practice, the operating lever 12 would preferably be secured in its operative position, when the car is loaded, by means of a seal. This seal may be applied in a good many different ways and may be conveniently applied by passing the wire 23 of the seal through a staple 24 on the door section 13^b and through the depending perforated end of said lever 12. With this complete door, and with the seal applied, the usual outer or sliding car door may be dispensed with.

In the modification illustrated in Figs. 8 and 9, the hinge rod 15^a, instead of having eyes in its ends, is provided with small spur pinions 16^a. These pinions 16^a mesh with racks 25 that extend vertically upward and then curve inward and assume horizontal positions. These racks 25 are suitably secured to the door posts and are provided with flanges 26 that extend parallel to the teeth of said racks and engage the extreme ends of the rod 15^a, and thereby hold the pinions 16^a in engagement with the said racks, while permitting upward and downward movements of the grain door. In Fig. 8, the numeral 27 indicates a hook that is pivotally mounted in the door section 13 and is engageable with a yoke 28 on the door section 13^a to lock the said two door sections together.

It is, of course, evident that the pressure of the grain on the several sections of the door will be outward and that it of course follows that the door section 13 will swing outward under the pressure of the grain, whenever the lock plates 5 are moved into their inoperative positions, shown in Fig. 7. This, of course, permits an initial discharge of grain

from the car and thus makes it unnecessary to pry up or slide any of the door sections while the pressure of the grain is against the same.

What I claim is:

1. The combination with a car body having stop cleats and pivoted lock plates applied to the sides of its door opening, of a lower grain door section adapted to be moved laterally through said door opening and to be clamped between said plates and co-operating stop cleats, guides for said grain door extending upward along the sides of the door opening and thence curving inward and extending approximately to the center of the car, whereby said door may have a sliding movement, and an upper grain door section mounted for sliding movement on independent guides, substantially as described.

2. The combination with a car body having stop cleats and pivoted lock plates applied to the sides of its door opening, of a lower grain door section adapted to be moved laterally through said door opening and to be clamped between said plates and co-operating stop cleats, guides for said grain door extending upward along the sides of the door opening and thence curving inward and extending approximately to the center of the car, whereby said door may have a sliding movement, an upper grain door section mounted for sliding movement on independent guides and also adapted to be moved laterally through said door opening, and locking means for securing said upper door section when in closed position to the pivoted lock plates, substantially as described.

3. The combination with a car, of a grain door seated in the door opening thereof, and pivoted lock and closure plates mounted on the sides of the door frame and engageable with the edges of said grain door, the said door and lock plates having interlocking parts which positively hold the door against vertical movement when such lock plates are in operative position, the same consisting of a stud or projection on one of the members and a perforation or recess in the other member which interlock upon the swinging merely of the lock plates.

In testimony whereof I affix my signature in presence of two witnesses.

JOHN EDMAN.

Witnesses:

MALIE HOEL,
F. D. MERCHANT.
